Primary Examiner — Ricky Pham(74) *Attorney, Agent, or Firm* — Patterson Thuente Pedersen, P.A.**CLAIM**

(57) We claim the ornamental design for popcorn popper, as shown and described.

DESCRIPTION

FIG. 1 is a front view of a popcorn popper according to a representative embodiment of the present invention.

FIG. 2 is a side view of the popcorn popper of FIG. 1.

FIG. 3 is a rear view of the popcorn popper of FIG. 1.

FIG. 4 is a side view of the popcorn popper of FIG. 1.

FIG. 5 is a top view of the popcorn popper of FIG. 1.

FIG. 6 is a bottom view of the popcorn popper of FIG. 1; and,

FIG. 7 is a perspective view of the popcorn popper of FIG. 1.

Items shown in broken lines are for illustrative purposes only and form no part of the claimed invention.
